PHOTOELECTRIC STORAGE DEVICE

Kurt Schlesinger, Berlin, Germany, assignor, by
mesne assignments, to Loewe Radio, Inc., a cor-
poration of New York

Application June 11, 1937, Serial No. 147,799
In Germany June 16, 1936

1 Claim. (Cl. 178—7.2)

The applicant has formerly proposed to employ a device for storing and scanning photo-electric charges which device consists in substance of a coherent and an incoherent photo-electric plate electrode, for example a mesh and a mosaic screen. The two plates are situated opposite and parallel to one another, and the photo-electric condenser thus formed is from the one side illuminated by the image light and from the other side scanned by a moving spot of light, which in turn may be produced, as a projection of the luminous screen image of a television cathode ray tube. This arrangement, while yielding quite satisfactory effects in the television transmission of scenes, is still subject to internal losses. These losses are due primarily to the fact that the two illuminations influence one another because none of them is completely absorbed by the electrode on which it impinges and each of them causes, partly reflected, a spurious discharge of the other electrode, so that the storage output will be reduced.

An object of the present invention is a tube construction avoiding the above disadvantage.

25 A further object of the invention is a tube acting in itself as an electronic amplifier of the current obtained by scanning the image.

The invention will be explained by means of the accompanying drawing of which

30 Fig. 1 shows an arrangement according to the invention,

Fig. 2 is a detailed cross-section of electrodes according to the invention including the circuit connected therewith,

35 Fig. 3 shows a modified circuit connection of the electrodes of the device according to Fig. 1, and

Fig. 4 the structure illustrated in Fig. 1 as combined with an electron amplifier system.

40 In Fig. 1, 1 is a network having a number of meshes which corresponds at least to the number of image points. The network consists of silver, or is silver-coated, and is photo-electrically activated in the usual manner by means of caesium. It functions as photo-electric cathode. In close proximity opposite to 1 there is provided a mosaic screen 2, which consists of at least as many small rods as there are image points to be transmitted. The rods are photo-electrically activated on its 45 rear side and are well insulated one against the other. Behind the screen 2, at a somewhat larger distance, there is arranged an anode 3 consisting of a wide network of thin wires. The whole assembly is enclosed within the vacuum vessel 4. 50

55 The image or scene 5 is projected onto the front

side of the net 1 by way of a lens 6, whilst the rear side of the screen 2 is scanned by a light spot projected onto it by means of the lens 7 from the luminous screen of a Braun tube 8 operated in the well known manner with constant ray intensity. The net 1 is directly earthed, the anode 3 via resistance 9 and anode battery 10. The operation is then as follows:

The light projected onto the net 1 causes an electron emission of the corresponding point of 10 1 according to the light intensity of each point, and this emission is absorbed the rods 2 forming anodes with respect to 1. The positive charges of the rods are due to the scanning light spot freeing electrons from the rods. Thus each rod 15 facing an illuminated part of the net 1 will, when recharged by the scanning spot, cause a current push through resistance 9 which is coupled at 21 to the video amplifier (not shown).

It is accordingly on the one hand necessary to 20 make the capacity between 1 and 2 very large, whilst on the other hand it is very detrimental to allow a large capacity between the different rods 2. In practice it would be very difficult to fulfil this condition without employing the construction of the screen according to Fig. 2.

In Fig. 2, 2a is a cross-section through a coherent net or sieve insulated on all sides. An appropriate insulation, when employing a sieve of aluminium, may be produced advantageously by 30 an electrical oxidizing process. It is, however, also possible to employ any other metal and to glaze the same, for example with enamel. The insulation of the sieve is represented by the surrounding curves 11. After this operation metallic silver is introduced into the intermediate spaces of the sieve, so as to completely fill out the previously open meshes. The silver is designated 35 2b. It replaces the rods 2 in Fig. 1. The introduction of the silver may take place, for example, 40 by reducing a paste of silver compound at high temperature or electrolytically or by atomization. After the introduction of the metallic plugs 2b the same are photo-electrically activated on the side facing the anode 3. The supporting sieve 2a 45 is, by means of lead 12, electrically connected with the net 1 and this way earthed, this screening-off the singled rods 2b against each other. The spacing between screen 2 and net 1 must accordingly be equal to or smaller than the mesh 50 width in order to avoid a straying of the primary electrons from one image point location to adjacent ones. In practice, even with the maximum number of lines presently used, i. e., with 400 lines, a spacing of $\frac{1}{16}$ mm. will be found suffi- 55

cient, as networks having meshes of less than $\frac{1}{16}$ mm. are not obtainable, corresponding to a net of about 50 x 50 mm. The plates may naturally also be made considerably larger, if only for the reason that the possibility then exists of displacing the one projection surface laterally in relation to the other, or also of optically increasing or reducing the scanned screen area without the occurrence of interfering marginal signals owing to the fact that the scanning light drops off the area. In this way novel effects may be obtained in the transmission of images.

Instead of coupling the amplifier to the anode 3 it may also, with the reciprocal effect be coupled 15 at 31 by means of a resistance 22 to the net 1, according to Fig. 3, with the disadvantage that a condenser 13 must be inserted in order to block-off the direct current.

A particularly important feature is the possibility of directly amplifying the electron currents supplied by plate 2 before they are conducted to a tube amplifier. In contradistinction to the known ikonoscope this screen plate supplies electron currents instead of voltage impulses, which 25 electron currents may be directly multiplied by secondary current multiplication whereby the ratio between signals and noises is considerably reduced. For this purpose it is firstly necessary to concentrate the electrons, which are leaving 30 the large area 2 by means of an electron-optical collecting lens on to a comparatively small focus point. As the applicant has found, this may be effected by the use of two co-axial rings 14, 15 (Fig. 4) in conjunction with an anode ring 16. 35 The height of the rings 14 is approximately equal to their radius. The first ring 14 is connected with a weak positive potential of about 10 volts relatively to earth. The next ring 15 and the anode ring 16 are furnished with increasing potential. By adjusting of the intermediate potential 15 it is possible to concentrate all electronic rays just in or behind the aperture of 16 into a space ten times smaller than the area 2. 40 At this point there may be provided a small intermediate anode 17, which becomes the origin of an amplified number of electrons. Methods of magnetically or electrically separating the primary and secondary electron rays are already known. An electric or magnetic deflection of the 45 primary rays may also take place before the impinging on 17, for example to the extent of 90°, by means of a magnetic field (not shown) disposed perpendicularly to the plane of the paper, so that the next intermediate anode is situated at 18 and the secondary electrons emitted from the latter impinge on 24. The last anode 25 is connected to the most positive terminal of the battery 10, the intermediate anodes to progressive intermediate potentials, and the output 21 to the 50 signal amplifier. In this arrangement the anodes

are so disposed that the screen 2 is freely accessible to the light from the scanned area projected into the tube by the lens 7.

I claim:

A television system comprising an evacuated tube member, a photoelectrically activated mesh-like electrode element within the tube, a connection from said element to a point of equilibrium potential, means to illuminate said element with the light of an optical image to release photo-electrons therefrom, a mosaic electrode element within the tube in close proximity to and substantially parallel to said mesh-like element to collect electrons released from the mesh-like element under the influence of light, said mosaic element also comprising a mesh-like support and having an insulating coating about the mesh and metallic elements extending within and protruding through the interstices of the mesh to a plane at least co-planar with the plane of the mesh, 20 said metallic elements being insulated one from the other by the insulating coating, a photo-electric coating upon the ends of the metallic elements which are remote from the photoelectrically activated mesh-like electrode, an apertured anode element, a source of scanning light to illuminate the photoelectrically activated areas of the mosaic according to a predetermined light traversal pattern and to release electrons therefrom at areas of light impingement, the quantity 25 of electrons instantaneously released by the scanning light being measured by the amount necessary to raise the potential of the mosaic element to substantially anode potential from a more negative value due to collecting photoelectrons from the mesh-like electrode element, a second anode element of an area relatively small compared to the mosaic electrode element, means to maintain the second anode positive with respect to the first anode, focusing electrode means 30 intermediate the mosaic and the first anode to focus the electrons released from the mosaic by the scanning light through the first apertured anode and upon the second anode so that the electron stream released from the relatively large mosaic area is concentrated upon the reduced area second anode and secondary electrons are released therefrom by the impact thereon of the said initially released electrons, said second anode being in non-parallel 35 relation relative to the mosaic to redirect the electron flow reaching said second anode along a diverted path, electrode means for producing by secondary emission further intensification of the electron flow, an output electrode and a direct 40 connected load circuit for amplifying the resultant output energy available at the output electrode.

KURT SCHLESINGER.
